DISPLAY STAND

Ronald M. Johnson, Minneapolis, Minn., assignor to The Toro Company, South Minneapolis, Minn.

Filed Jan. 17, 1972, Ser. No. 218,647

Term of patent 14 years

Int. Cl. D6—99

U.S. Cl. D6—28

FIG. 1 is a front view of a display stand embodying my design;

FIG. 2 is a side view thereof;

FIG. 3 is a top view thereof;

FIG. 4 is a bottom view thereof;

FIG. 5 is a back view thereof; and

FIG. 6 is a frontal perspective view thereof illustrating a reel mower being supported by the display stand.

The broken line illustration, FIG. 6, of the display stand with a reel mower supported thereby illustrates the intended use of the claimed design and is shown for illustrative purposes only.

I claim:

The ornamental design for a display stand, as shown and described.
